SNATCH BLOCK

Edward L. Vick, 4861 Seven Hills Road, Castro Valley,
Calif. 94546, and Arlie E. Smith, 3791 Mosswood
Drive, Lafayette, Calif. 94549

Filed May 19, 1975, Ser. No. 578,394

Term of patent 14 years

Int. Cl. D12—05

U.S. Cl. D8—216

Fig. 1

Fig. 2

Fig. 3

Fig. 4

Fig. 5

FIG. 1 is a front elevation of a snatch block showing our new design;

FIG. 2 is a rear elevation thereof;

FIG. 3 is a side elevation thereof, the opposite side elevation of the block appearing the same;

FIG. 4 is a top plan view thereof; and

FIG. 5 is a bottom plan view thereof.

We claim:

The ornamental design for a snatch block, as shown and described.
